BALL CATCHING BASKET

William J. Miller, 1270 Syracuse St., Denver, Colo.

Filed Mar. 28, 1960, Ser. No. 59,906

Term of patent 14 years

(Cl. D34—5)

Fig. 1 is a perspective view of a ball catching basket showing my new design with a strap portion omitted to show the device as it would appear on a head, which is shown in broken lines for illustrative purposes only; and

Fig. 2 is another perspective view thereof.

I claim:

The ornamental design for a ball catching basket, as shown and described.
